Patented Feb. 26, 1924.

UNITED STATES PATENT OFFICE.

EDWARD F. MOSER, OF WARSAW, INDIANA.

YIELDING STRAP FOR SUSPENDERS AND THE LIKE.

Application filed May 8, 1922. Serial No. 559,238.

To all whom it may concern:

Be it known that I, EDWARD F. MOSER, a citizen of the United States, and a resident of Warsaw, county of Kosciusko, and State of Indiana, have invented a certain new and useful Yielding Strap for Suspenders and the like; and I do hereby declare that the following is a full, clear, and exact description thereof, reference being had to the accompanying drawings, in which like numerals refer to like parts.

This invention relates to a yielding strap construction for suspenders and the like, and the chief object of the invention is to construct a yielding strap construction in such a manner that the same is not only artistic in appearance but also utilizes the tension of the spring associated therewith.

The chief feature of the invention consists in the use of a double or plural tension and elastic construction, and a further feature of the invention consists in the construction of a strap in such a manner that there are provided two overlapping straps in which the double tension and elastic construction is secured in a manner hereinafter to be described.

A further feature of the invention is that the strap or suspender may be made of a metallic spring, thereby making said strap or suspender substantially everlasting in use, whereas heretofore when the elastic medium has been incorporated in the cloth or other material forming the strap or suspender, said elastic material generally being of rubber or rubber-like material, deteriorated with the passage of time whether or not the article was in use, and such deterioration increased with use, said elastic being further susceptible to perspiration, dies and the like which further increase the rate of deterioration of the strap or suspender, and thereby shortens the life of the same.

Another feature of the invention is that the same may be constructed so that either or both of the double tension and elastic constructions may be exposed or covered as desired, and said elastic construction may be rigidly or detachably anchored to the strap construction, as desired. The construction is such that the strap portion or portions may be made of any suitable or desired material, such as cotton, silk, leather or any other, thus being applicable to the several demands of the several different classes of trade.

A further feature of the invention is the two-way stretching of the construction, and a further feature thereof is that as shown the extension of the construction is impossible beyond the limit due to the dual connections thereby maintaining the springs or flexible means at their maximum power at all times by preventing stretching the same beyond the elastic limit thereof.

The full nature of this invention will be understood from the accompanying drawings and the following description and claims.

In the drawings Fig. 1 is a side elevational view of a portion of the suspender construction embodying the invention, the latter being shown dotted where hidden. Fig. 2 is a longitudinal sectional view taken on line 2-2 of Fig. 1 and shows the relationship of the several elements as well as both springs in covered relation. Fig. 3 is a longitudinal sectional view of a similar construction with one spring exposed and the other covered or enclosed. Fig. 4 is a longitudinal sectional view of a similar construction showing both springs exposed. Fig. 5 is a longitudinal sectional view of a modified construction wherein the springs are replaced by an elastic band.

In the drawings there is illustrated a pair of straps 10 which herein are shown crossed and secured together at 11 in the usual manner for suspenders, over-alls and the like. Each of the straps 10 is associated with another strap herein indicated by the numeral 12. The strap 12 is provided with an end 13 or 113. The end 13 is shown forming a loop adapted to receive the usual button engaging element 14 having flat terminating ends 15 apertured at 16 for the reception of the button. The end 113 is of a different type and is provided with a button hole 114 for the reception of the button. Any other suitable or desired button engaging means may be substituted for the construction herein described without departing from the broad idea of the invention.

In detail the yielding construction consists of the two straps 10 and 12. Associated with the strap 10 is a cover portion 20 and associated with the strap 12 is a cover portion 22. The portions 20 and 10 are secured together and form a single strap. The portions 22 and 12 are secured together and form a single strap. At the junction of the portions 20 and 10, see Fig. 2, there is secured

and preferably simultaneous with the junction, a loop 21. The loop 21 is connected to one end 23 of the spring 24. Herein such spring is shown as a coil spring, although any other form of spring may be utilized. The other end 25 of the spring 24 is secured to the hook 26 carried by an elongated loop 27. The elongated loop 27 encloses or surrounds the cover strap 20, as shown. The cover strap 20, after passing through the loop 27, passes behind the cover 22 and the other strap 12 and thereby overlaps said last mentioned portions, and said cover 20 is joined to or is integral with the strap 10. At the loop or end 28 formed by the junction of these two straps 20 and 10 at the overlapping portion, there is secured an elongated loop 29 having the hook portion 30.

20 The strap and cover portions 12 and 22 respectively are similar to that hereinbefore described and at the junction there is secured a loop 31 which is connected to one end of the coil spring 34, the other end 35 of which is connected to the hook 30 of the loop 29. The cover portion 22 is extended parallel to the other strap portions and is passed through the loop 27 at 36. The portion 12 also passes through the loop 29 at 37 and said cover 22 and strap 12 are suitably joined together or are integral. The portion 36 preferably forms a loop by being secured together at 38, while the portion 28 forms a loop by being secured together at 39. From the foregoing it will be understood that both of the springs 24 and 34 are covered and also they are covered in such a manner that the same are not exposed either to observation or to the body of, or garment upon the wearer. It will likewise be understood that the spring ends 23, 25, 33 and 35 may be either rigidly or detachably associated with the several spring end supports. For replacement purposes detachable connections 45 are preferred.

In Fig. 3 there is illustrated a modified form of the invention and in this form of the invention it will be noted that one of the springs is exposed while the other spring is covered. Herein a strap 110 is provided with a cover portion 120 and said cover portion passes through a loop 27 and after passing through the loop 27 forms a loop 128 by the sewing 130. The strap 110 and the continuation of the strap 120 are secured together or may be a continuation of each other. The loop 128 supports the loop 29 of the hook forming member provided with the hook 30. The other strap 112 after passing through the loop 29 overlaps the cover strap 120 and at 136 forms a loop. Said strap terminates at 138 and is suitably secured in said loop formation by the sewing. The loop 136 is secured to the hook member 27 provided with the hook 26. Between the

straps 110 and 120 there is positioned a loop 121 which may be of metal or fabric. The loop 121, in the same manner as the loop 21, supports one end 23 of the tension spring 24, the other end 25 of which is associated with the hook 26 of the hook forming member 27. The strap 112, instead of the loop 31, herein is shown provided with a hook member 131 which is suitably secured thereto in the usual manner such as that of the hook and eye construction secured to any garment. The hook 131 is secured to the end 33 of the other tension spring 34, the other end 35 of which is supported by the hook 30 of the hook forming member 29. The aforesaid construction, therefore, shows one spring exposed and one spring covered.

In Fig. 4 there is illustrated another form of the invention wherein both springs are exposed or uncovered. Herein the usual strap or loop 21 of Fig. 2 and 121 of Fig. 3 is replaced by the hook 221 similar to the hook of a hook and eye construction. The strap 210 is secured to the hook 221 and a continuation thereof passes through the loop 27 of the hook forming member having the hook 26. After passing through the loop 27 of said member, the end of the strap 210 terminates in a loop 228 formed by the sewing 239. The loop 228 is adapted to receive the loop 29 of the hook forming member having the hook 30. The hook 30 supports one end of the coil spring 34, and the other end 33 of which is secured to a hook member 231, substantially similar to the hook member 221. The hook member 231 is suitably secured to the strap 212 intermediate its length and the strap 212 is extended and passes through the loop 29 and terminates in a loop 236 formed by the sewing 238. The loop 236 is secured to the loop 27 of the hook forming member having the hook 26, which hook secures one end 25 of the coil spring 24, the other end 23 of which is secured to the hook 221 substantially similar to the hook 231.

In Fig. 5 there is shown a modified form of the invention. In this form of the invention the spring means is replaced by an elastic construction. In said figure 310 is one strap and 320 is the return portion thereof, which are sewed together at 339 to form the loop 328 adapted to receive the loop securing member 329, which secures one end of the elastic member 334, the other end of which is simultaneously secured to the strap 312 and cover 322, as shown.

It will be noted that in each instance there is provided substantially plural strap constructions which are separable, but which are connected together at a plurality of points by plural tension means. It will also be observed that the strap portions overlap one another in each instance. In Fig. 2 there is shown four overlapping portions. In Fig. 130

3 there is shown three overlapping portions while in Fig. 4 there is shown two overlapping portions. It will also be understood that the position of the exposed and covered 5 springs 24 and 34 shown in Figs. 3 and 4 may be reversed without departing in any manner from the invention. It will likewise be observed that while coil springs are illustrated, any form of springs may be substituted therefor and the number thereof 10 may be increased, if desired, or any other suitable material capable of expanding and contracting such as the elastic (shown in Fig. 5) may be substituted for the springs 15 without departing from the broader features of the invention.

While the invention has been described in great detail in the foregoing specification, it will be understood that all modifications 20 described and suggested hereinbefore, as well as all the modifications which will readily suggest themselves to those skilled in the art to which this invention applies, are considered to be within the broad purview of 25 the invention as outlined by the appended claims. In the claims the term "elastic" is intended to include a spring or a rubber construction which normally resumes its original form upon release from a stretching 30 movement, unless said movement is sufficient to permanently deform the elastic construction.

The invention claimed is:

1. A yielding strap construction including a plurality of elastic means in tandem and 35 separated relation, and strap means between the same and associated therewith, the strap means being arranged to permit relative movement between the elastic means and the strap means but prevent stretching the 40 elastic means beyond a predetermined limit.

2. A yielding strap construction including two straps which double upon themselves with the doubled ends overlapping, and a pair of elastic means each secured to 45 a strap within the doubled portion thereof and to the other strap at the overlapping portion.

3. A yielding strap construction including two overlapping straps, one of which is 50 doubled upon itself, and an elastic means within said doubled portion and secured to the other strap at the overlapping portion.

4. A yielding strap construction including a pair of straps, a pair of looped securing 55 members, and a pair of elastic means each secured at one end to a securing member and at the opposite end to the strap, each passing through the adjacent loop member and being connected to the other loop member. 60

In witness whereof, I have hereunto affixed my signature.

EDWARD F. MOSER.
